SHAVING BRUSH

Frederick J. Collins, Toronto, Ontario, Canada

Application March 10, 1949, Serial No. 1,344
In Canada September 9, 1948

Term of patent 7 years

(Cl. D9—2)

To all whom it may concern:

Be it known that I, Frederick J. Collins, a citizen of Canada, residing at Toronto, in the county of York and Province of Ontario, Canada, have invented a new, original, and ornamental Design for Shaving Brushes, of which the following is a specification, reference being had to the accompanying drawing, forming part thereof.

The figure is a perspective view of a shaving brush, showing my new design.

The two sides of the shaving brush not shown in the drawings are identical with the corresponding sides shown.

I claim:

The ornamental design for a shaving brush, as shown and described.

FREDERICK J. COLLINS.
